UNITED STATES PATENT OFFICE.

ADOLPHIE PAROUTAUD, OF NEW YORK, N. Y.

DESIGN FOR A COVERED DISH.

SPECIFICATION forming part of Design No. 29,967, dated January 10, 1899.

Application filed December 15, 1898. Serial No. 699,385. Term of patent 3 $\frac{1}{2}$ years.

To all whom it may concern:

Be it known that I, ADOLPHIE PAROUTAUD, of the city of New York, borough of Manhattan, in the county and State of New York, have invented and produced a new and original Design for a Covered Dish, of which the following is a specification, reference being had to the accompanying drawings, forming a part thereof, in which—

10 Figure 1 is a plan view of a covered dish embodying the features of my design, and Fig. 2 is a side elevation thereof.

The leading feature of the design consists in the shape and ornamentation of the body

15 A. The body has a decided upward swell formed upon convexed lines extending from the base to a point near the top and a decided upward and inward inclination from the upper termination of said swell, as at a. The 20 upper portion of the swell-section of the body is interrupted at intervals by embossed ornaments B, that vanish near the base.

The minor feature of the design consists in the formation of the base, which is at an angle to the body and is provided with a scalloped margin, together with a cover for the dish the margin whereof is undulating, the upper marginal portion of the cover and the inclined upper surface a of the body having floral and scroll decorations thereon. Ribbon-like handles appear at the ends of the body of the dish, and a ribbon-like handle also appears at the upper central portion of the cover, and beneath the handle of the cover and surrounding it a representation of 35 drapery is produced upon said cover.

I claim—

The design for a covered dish herein shown and described.

ADOLPHIE PAROUTAUD.
